UNITED STATES PATENT OFFICE.

WILLIAM M. DOUCETTE, OF YONKERS, NEW YORK.

DESIGN FOR A TIRE-TREAD.

59,065.

Specification for Design. Patented Sept. 20, 1921.

Application filed July 29, 1920. Serial No. 399,899. Term of patent 14 years.

To all whom it may concern:

Be it known that I, WILLIAM M. DOUCETTE, a citizen of the United States of America, residing at Yonkers, in the county of Westchester and State of New York, have invented a new, original, and ornamental Design for Tire-Treads, of which the following is a specification, reference being had to the accompanying drawings, forming a part thereof, in which—

Figure I. is a plan view of a portion of my tire tread.

Fig. II. is a cross section along the line 2—2 in Fig. I.

I claim:

The ornamental design for a tire tread, as shown.

WILLIAM M. DOUCETTE.
